US0D1009420S

(12) United States Design Patent (10) Patent No.: US D1,009,420 S
(45) Date of Patent: * Jan. 2, 2024

(54) PORTION OF A SHOE

(71) Applicant: ROTHY'S, INC., San Francisco, CA (US)

(72) Inventors: Stephen Hawthornthwaite, San Francisco, CA (US); William Roth Martin, San Francisco, CA (US)

(73) Assignee: ROTHY'S, INC., San Francisco, CA (US)

() Term: 15 Years

(21) Appl. No.: 29/693,535

(22) Filed: Jun. 3, 2019

Related U.S. Application Data

(63) Continuation-in-part of application No. 29/646,868, filed on May 8, 2018, now Pat. No. Des. 903,278, and a continuation-in-part of application No. 29/641,383, filed on Mar. 21, 2018, now Pat. No. Des. 884,317.

CLAIM

The ornamental design for a portion of a shoe, as shown and described.

DESCRIPTION

FIG. 1 is rear left perspective view of a portion of a shoe showing our new design;

FIG. 2 is front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The broken lines shown in the figures are included for the purpose of illustrating portions of the portion of a shoe and form no part of the claimed design.

1 Claim, 7 Drawing Sheets
